UNITED STATES PATENT OFFICE.

CHARLES B. COATES, OF ERIE, PENNSYLVANIA, ASSIGNOR TO CHICAGO PNEUMATIC TOOL COMPANY, OF NEW YORK, N. Y., A CORPORATION OF NEW YORK.

MAGNETIC CONNECTER.

Application filed May 18, 1922. Serial No. 561,801.

To all whom it may concern:

Be it known that I, CHARLES B. COATES, a citizen of the United States, residing at Erie, county of Erie, and State of Pennsylvania, have invented certain new and useful Improvements in Magnetic Connecters, of which the following is a specification.

This invention relates to magnetic connectors and more particularly to a novel and simple connector adapted to magnetically adhere to an electrical conductor without the use of bolts, clamps, or other mechanical fastening devices which would require the employment of a wrench, etc., or manual manipulation. A further object of my invention is to construct the magnetic connector so that it is adapted to form part of the electric circuit and a terminal through which the current is supplied. My invention is peculiarly adapted for use in connection with electric railway construction, and while it has uses in connection with innumerable other kinds of work I will describe its use in connection with such construction, merely for the sake of convenience and by way of illustration. Electrical portable tools, such as drills, grinders and spike drivers, are used to a large extent in constructing and repairing electric railway and the equipment therefor and one terminal of the ground wire on the tool is usually connected to one of the rails (which form the ground or return circuit). The surface of the pavement, particularly in cities, is usually even with the tops of the rails so that it is practically impossible to clamp or mechanically attach a connector to the rail. As a make-shift, a workman usually connects a bolt or piece of metal to the ground wire or cable on the tool and lays it on the rail, which is not satisfactory as there is nothing to firmly hold the bolt or piece of metal on the rail and the connection is not satisfactory electrically. With my invention it is only necessary to bring the permanent magnets of the connector into engagement with the rail or other electric conductor and the magnets cause the connector to strongly adhere to the rail. One terminal of a coil, forming part

of the electrical circuit through the electric tool or other device, is grounded to the core of my connector so that when the electric device is started the current passes through the electric tool thence through the core and

magnet so that the connector becomes a very strong electromagnet due to the current passing through the coil. Hence a connector, constructed in accordance with my invention, is quickly and easily attached to the electrical conductor by the mere act of placing the connector thereon and at the same time the connector constitutes a ground connection for the electric current.

In the drawings, Fig. 1 is a side elevation of a connector, embodying my invention and showing the coil in cross section; and Fig. 2 is in the nature of a diagrammatic view showing the connector resting on a railway rail and in association with an electric tool.

Referring to the drawings, the connector comprises two permanent magnets 3 to the opposite ends of which an iron core 4, preferably of soft iron, is attached, the magnets being secured to the core by screws 5 and washers 5'. Wound around the core is a coil 6 having one terminal 7, the inner one, grounded to the core while the outer one 8 is connected to the cable 9 leading from the electric portable tool 10 of any construction or kind. Disks of insulating material 11 are positioned between the ends of the coil 6 and the magnets 3. As shown in Fig. 2, the permanent magnets 3 are adapted to rest on top of the rail 14, shown in cross section. In this view the paving 12 is shown on both sides of the rail as having its upper surface practically even with the top of the rail. The wire 13 leading to the electric tool is usually connected at its upper end to the trolley wire, when the connector is used in electric railway work.

From the above description it is obvious that the permanent magnets 3 cause the connector to adhere with considerable force to the rail and that when the electric tool is started the current passes from the trolley wire through the wire 13 and the tool thence through the wire 9, terminal 8, the coil 6, terminal 7, the core 4 and the magnets 3 to the rail. The current causes the connector to become a very strong electromagnet so that the connector adheres to the rail with great tenacity. Permanent magnets in time lose their magnetism to a considerable extent, but each time my magnetic connector is used these magnets are re-magnetized so that they are always well

magnetized which causes the connector to adhere strongly to the rail even when the tool is not in operation. My connector not only forms a magnetic connector but is 5 adapted to constitute the ground connection for the electrical circuit passing through the electric tool or other device. The use of clamps, wrenches, etc., and tools for attaching a connector to the electrical 10 conductor, when the conductor is such as to permit such an attachment, is dispensed with, thus saving considerable time and expense and eliminating inconvenience, annoyance and danger. Where bolts, clamps 15 or other securing devices cannot be employed, as in the above described example, a connector embodying my invention has even greater utility.

I claim:

- 20 1. In a device of the class described, the combination of a permanent magnet adapted to be magnetically attached to an electrical conductor forming part of the electrical circuit, and a coil associated with 25 said magnet and having one terminal electrically connected thereto.
- 20 2. In a device of the class described a core, permanent magnets secured to said core and adapted to be magnetically attached to an electrical conductor forming part of the electrical circuit and a coil wound around the core and having one terminal grounded thereto.
- 25 3. In a device of the class described, the combination of a magnetizable core, permanent magnets directly secured to and supporting opposite ends of the core and adapted to be magnetically secured to an electrical conductor and a coil forming part of 40 the electrical circuit and having the inner terminal grounded to said core while the outer terminal is adapted to be connected to

an electrical device to be operated by the electrical circuit.

4. An electrical connector of the type described comprising a member of magnetizable material adapted for contact with an electrical conductor, a coil associated with said member for magnetizing the same, one terminal of said core being electrically connected to said member whereby on passage of an electric current through the coil the connector makes electrical as well as magnetic connection with the conductor.

5. The combination with an electrically operated device of connector means therefore adapted to make and maintain an electrical connection when placed in contact with an electrical conductor, said means comprising a member of magnetizable material having a coil associated therewith, the terminals of said coil being electrically connected to said member and to said device respectively.

6. The combination with an electrically operated device of a connector therefor comprising a permanent magnet adapted to be magnetically attached to an electrical conductor forming a part of the circuit of the device, and a coil associated with said 70 magnet and having its terminals electrically connected to said magnet and to said device respectively.

7. The combination with an electrically operated tool of a connector therefor comprising a core, permanent magnets secured to said core and adapted to be magnetically attached to an electrical conductor forming a part of the circuit of the tool, and a coil wound around the core and having its terminals electrically connected to said core and to said tool respectively.

CHARLES B. COATES.
